UNITED STATES PATENT OFFICE

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

THREAD CUTTING MECHANISM

Application filed January 23, 1931. Serial No. 510,740.

This invention relates to a mechanism for cutting weft ends extending from the selvage of a piece of cloth in an automatic loom.

The invention relates more particularly to 5 a filling-mixing, two-by-two loom in which two shuttles are picked alternately on successive picks, first to one side of the loom and then to the other, and in which the filling replenishment of both shuttles takes place at 10 the same side of the loom and preferably from one two-cell magazine.

It is desirable that the selvage thread cutter operate to cut the weft ends of both the ejected and the freshly inserted weft carriers at a time when there is no chance of 15 cutting the active weft thread extending to either shuttle.

Accordingly it is the object of my invention to provide a thread cutting mechanism 20 at the cloth selvage, so designed and connected that it will become operative once only in every four picks of the loom, and that it will thus become operative on the pick when both shuttles are at the opposite side of the 25 loom from the thread cutter.

A further object of the invention is to attain the above outlined result by the use of a very simple and entirely reliable mechanism.

30 With these general objects in view, my invention consists in certain arrangements and combinations of parts which will be herein-after described and more particularly pointed out in the appended claims.

35 A preferred form of the invention is shown in the drawings, in which.

Fig. 1 is a plan view of parts of a loom embodying my improvements;

40 Fig. 2 is a sectional end elevation, taken along the line 2—2 in Fig. 1;

Fig. 3 is a diagrammatic view to be described;

45 Fig. 4 is a side elevation of a selvage thread cutter, adapted for use in connection with my invention;

Fig. 5 is a plan view thereof;

50 Fig. 6 is a side elevation of the thread cutter, looking in the direction of the arrow 6 in Fig. 5; and

Fig. 7 is a perspective view of the cutter member.

Referring to the drawings, I have shown portions of a two-by-two filling-mixing drop-box loom comprising a loom frame 10, a lay 55 11, drop boxes 12, and a two-cell filling-replenishing magazine M having an end holder 14. The lay 11 is oscillated in the usual manner from a continuously rotated crank shaft 16 (Fig. 2) which is geared in one-to-two relation to the usual bottom or cam shaft 18, this cam shaft thus rotating at half the speed of the crank shaft.

A selvage thread cutter T is mounted on the breast beam 20 of the loom adjacent the 65 edge of the cloth C. The thread cutter itself is of the usual commercial type, and comprises a stand 22 in which a supporting bar 23 is slidably mounted, which bar is normally pushed rearward by a compression spring 24. 70

A cutter bar 25 (Fig. 7) is provided with hook-shaped cutting blades 26 and a depending contact portion 27. The cutter bar is 75 slidable in guideways formed in the rear end portion of the head 30 of the supporting bar 23, and the cutter blades 26 cooperate with a cutter blade 31 fixed to the head 30 when the depending portion 27 is engaged by a forwardly-moving lay.

A spring 32 is coiled about a stud 33 on the side of the bar 23, and the end of this spring 32 engages a stud 35 in the side of the depending portion 27 of the cutter bar. The spring 32 normally holds the cutters in the rearward open position indicated in Fig. 4. 80

A latch 40 (Fig. 2) is pivoted at 41 on the breast beam 20 and is normally held in position to engage the lower end of the cutter bar portion 27 by a tension spring 42. The latch 40 is provided with a depending arm 44 to which the upper end of a link 45 is connected. At its lower end, the link 45 is provided with an end portion 46 having an elongated slot 47 formed therein. A crank pin 48 is fixed in the side of a gear 49 and extends into the slot 47. The gear 49 meshes with a pinion 50 on the cam shaft 18, the gear and pinion having a ratio of two-to-one, so that the gear 49 makes one revolution for every four revolutions of the crank shaft 16. 95

and hence makes one revolution for every four beats of the lay 11.

The loom is provided with the usual clamping device 60 (Fig. 1) for holding the end of the out-going weft W, while the end holder 14 similarly holds the end of the incoming weft W'.

Having described the details of construction of my improved thread cutting mechanism, it will be evident that the thread cutter T is held in forward inoperative position by the latch 40, except when the crank pin 48 engages the upper end of the slot 47 and moves the latch to release the thread cutter. It will also be apparent that such engagement takes place once only for each revolution of the gear 49, and consequently takes place once only for each four revolutions of the crank shaft 16 and for each four beats of the lay 11, or once for each four picks of the loom.

Accordingly I have provided mechanism for releasing a selvage thread cutter on every fourth pick and for allowing the thread cutter to be operated by the lay once only after each release. The advantages arising from such restricted operation will be apparent from reference to Fig. 3, which illustrates diagrammatically the movements of the shuttles in a two-by-two, filling-mixing loom.

The drop boxes are indicated at 12 and 12^a at the two sides of the loom, and the shuttles are marked by the letters R and G, indicating red and green shuttles.

It will be understood that both shuttles may carry the same kind of filling, and that the designations R and G are merely for the purposes of description.

The magazine M and the thread cutter T are also indicated as being located at the left hand side of Fig. 3, the diagrams of which indicate the positions of the shuttles and drop boxes in successive picks.

In the upper diagram, both shuttles are at the right hand or non-replenishing side of the loom, with the shuttle R about to be picked. The second diagram shows the red shuttle at the magazine end of the loom, and the green shuttle about to be picked to the magazine end. The third diagram shows both shuttles at the magazine end, with the red shuttle about to return to the opposite end; and the fourth diagram shows the red shuttle at the right hand side of the loom and the green shuttle in flight toward the right hand side.

It will be evident that after the movement of the shuttles indicated in the fourth or lower diagram, the two drop boxes 12 at the magazine and thread cutting side of the loom will be vacant, so that there will be no weft at the left hand side extending from the selvage to either active shuttle.

The gear 49 carrying the crank pin 48 is so meshed with reference to the movements

of the shuttles and drop boxes that the thread cutter T will be released as the shuttle G starts for the right hand box. The thread cutter will then operate to cut the weft ends W and W' as the lay thereafter reaches front center and while the shuttles are both in the right hand boxes 12^a.

The thread cutter will then be held inoperative during the next three picks, represented by the three upper diagrams in Fig. 3, and will be again released as both shuttles are again boxed in the right hand boxes 12^a.

I am thus able to cut both the out-going and in-coming weft ends at a time when both adjacent shuttle boxes are empty and when there is no possibility of cutting the active wefts.

Having thus described my invention and the advantages thereof, I do not wish to be limited to the details herein disclosed otherwise than as expressed in the claims; but what I claim is:—

1. In a weft replenishing loom, a selvage thread cutter, and means to cause actuation of said thread cutter on every fourth pick only of said loom.

2. In a weft replenishing loom, a selvage thread cutter operable by engagement with a forwardly moving lay, means to render said thread cutter inoperative, and means to release said thread cutter for operation on every fourth pick of the loom.

3. In a filling-mixing, two-by-two loom, a selvage thread cutter operable by engagement with the forwardly moving lay, means to hold said thread cutter out of action, and means to release said thread cutter on every fourth pick only of the loom.

4. In a filling-mixing, two-by-two loom, a selvage thread cutter operable by engagement with the forwardly moving lay, means to hold said thread cutter out of action, and means to release said thread cutter on every fourth pick only of the loom and when both shuttles are at the opposite side of the loom from the thread cutter.

5. The combination in a loom as set forth in claim 4, in which said latter means includes a latch and an actuating member therefor, geared in four-to-one ratio to the crank shaft of the loom.

In testimony whereof I have hereunto affixed my signature.

ALBERT A. GORDON.
